(57) **CLAIM**

The ornamental design for a combination canister and bracket having holding features, as shown and described.

DESCRIPTION

FIG. 1 is a perspective view of a canister, according to an embodiment of the disclosed subject matter.

FIG. 2 is a rear view of the canister of FIG. 1, according to an embodiment of the disclosed subject matter.

FIG. 3 is a front view of the canister of FIG. 1, according to an embodiment of the disclosed subject matter.

FIG. 4 is a left side view of the canister of FIG. 1, according to an embodiment of the disclosed subject matter.

FIG. 5 is a right side view of the canister of FIG. 1, according to an embodiment of the disclosed subject matter.

FIG. 6 is a top plan view of the canister of FIG. 1, according to an embodiment of the disclosed subject matter.

FIG. 7 is a bottom plan view of the canister of FIG. 1, according to an embodiment of the disclosed subject matter.

FIG. 8 is an exploded perspective view of the combination of the canister of FIG. 1 and the bracket of FIG. 19, according to an embodiment of the disclosed subject matter.

FIG. 9 is an assembled perspective view of the combination of the canister of FIG. 1 and the bracket of FIG. 19, according to an embodiment of the disclosed subject matter.

FIG. 10 is a perspective view of a canister, according to an embodiment of the disclosed subject matter.

FIG. 11 is a rear view of the canister of FIG. 10, according to an embodiment of the disclosed subject matter.

FIG. 12 is a front view of the canister of FIG. 10, according to an embodiment of the disclosed subject matter.

FIG. 13 is a left side view of the canister of FIG. 10, according to an embodiment of the disclosed subject matter.

FIG. 14 is a right side view of the canister of FIG. 10, according to an embodiment of the disclosed subject matter.

FIG. 15 is a top plan view of the canister of FIG. 10, according to an embodiment of the disclosed subject matter.

FIG. 16 is a bottom plan view of the canister of FIG. 10, according to an embodiment of the disclosed subject matter.

FIG. 17 is an exploded perspective view of the combination of the canister of FIG. 10 and the bracket of FIG. 19, according to an embodiment of the disclosed subject matter.

FIG. 18 is an assembled perspective view of the combination of the canister of FIG. 10 and the bracket of FIG. 19, according to an embodiment of the disclosed subject matter.

(Continued)

FIG. 19 is a perspective view of a bracket having holding features.

FIG. 20 is a front elevation view of the bracket of FIG. 19. FIG. 21 is a rear elevation view of the bracket of FIG. 19. FIG. 22 is a right side elevation view of the bracket of FIG. 19.

FIG. 23 is a left side elevation view of the bracket of FIG. 19.

FIG. 24 is a top plan view of the bracket of FIG. 19.

FIG. 25 is a bottom plan view of the bracket of FIG. 19.

FIG. 26 is a detailed perspective view of an upper edge of FIG. 19, as represented by the dot-dash-dot line of FIG. 19. FIG. 27 is a detailed perspective view of a lower edge of FIG. 19, as represented by the dot-dash-dot line of FIG. 19.

FIG. 28 is a detailed plan view of the upper edge in top plan view, as represented by the dot-dash-dot line of FIG. 24; and,

FIG. 29 is a detailed plan view of the lower edge in bottom plan view, as represented by the dot-dash-dot line of FIG. 25.

The broken lines in the drawings illustrate the portions of the combination canister and bracket having holding features that form no part of the Claim.
